(57) **CLAIM**

The ornamental design for an ophthalmic surgical sponge, as shown and described.

DESCRIPTION

FIG. 1 is a perspective view of an ophthalmic surgical sponge, showing the design;

FIG. 2 is a left-side elevational view of the sponge of FIG. 1;

FIG. 3 is a front elevational view of the sponge of FIG. 1, the rear elevational view being a mirror image thereof;

FIG. 4 is a right-side elevational view of the sponge of FIG. 1;

FIG. 5 is a top-plan view of the sponge of FIG. 1; and, FIG. 6 is a bottom plan view of the sponge of FIG. 1.
